UNITED STATES PATENT OFFICE

THOMAS B. BROWN AND MARION L. STANSELL, OF DAYTON, OHIO

PARACHUTE OPENER

Application filed October 1, 1930. Serial No. 485,668.

This invention relates to new and useful improvements in parachute openers.

It is the principal object of our invention to provide means whereby helium or other gas under pressure may be employed to quickly force a parachute from a pack, then to assist in speedily opening it out and thereafter contributing to its buoyancy.

Our invention contemplates the attachment 10 to the parachute pack, of a tank of gas under pressure which, when the rip cord is pulled, will be released to fill and expand a flexible tubing that will force the canopy or sustaining sheet out of the pack and snap it open. 15 With the assistance of this gas filled cylinder, a parachute will be surely and quickly opened at low altitudes, while the buoyancy of the gas will assist in carrying the user safely to the ground.

20 Other important and incidental objects will be brought out in the following specification and particularly set forth in the subjoined claims.

In the accompanying drawing illustrating 25 our invention, Figure 1 is a perspective view of an open parachute, showing how our opener is embodied therein as well as how the gas tank is attached to a pack strapped to the back of the user. Figure 2 is a perspective 30 view of a portion of the canopy, showing how a branch of the flexible expanding tube is secured to it. Figure 3 is a perspective view of the discharge end of the gas tank, showing the valve opening means. Figure 4 is a 35 longitudinal sectional view taken through the release valve. And Figure 5 is a perspective view of the pack containing the parachute and our opening means.

40 Referring to the accompanying drawing for a detailed description of our invention, the numeral 1 designates a conventional parachute sustaining sheet or canopy from which sustaining cords 2 run to a ring 3. To the latter are attached the connected ends of 45 straps 4 whose lower ends are secured to a harness 5 that is worn by the user.

Referring to Figures 1 and 5, the numeral 6 designates a conventional pack secured to the harness 5. Mounted within this pack is 50 a small tank 7 filled with helium or other

suitable gas for assisting in the opening of the canopy.

Screwed into a tapped hole in one end 8 of the tank 7 is a plug valve 9 constructed as follows. Referring to Figure 4, this valve comprises a cylindrical member having a central bore communicating at its rear end with a counterbore 10. Projecting from the middle part of the body of the valve 9 is an inclined tubular extension 11 for a purpose herein-after to be described.

Longitudinally movable within the bore of the valve 9 is a cylindrical plug 12 between which and the shoulder at the rear end of the valve body is a helical spring 13. The latter is adapted to move the plug 12 forward to clear the bore 14 in the projection 11 when said plug is not restrained from such movement by a wire 15 that projects through two holes in the valve body. When released 70 by pulling the wire 15 through these holes, the plug 12 will be snapped forward by the spring 13 until it hits a cap 16 screwed on the front end of the valve body. In this position the valve plug 12 will permit gas under 75 pressure to flow from the tank 7 into the tubular extension 11 to which one end of a flexible tube 17 is connected.

The tube 17 projects upwardly under the canopy 1 where it is secured to an annular 80 flexible tube 18 which is stitched or otherwise secured to the under surface of said canopy near its fluted marginal edge. (See Figures 1 and 2.)

Secured under the middle top part of the 85 canopy 1 is a flexible compartment 19 which is in communication with the annular gas tube 18 through radial flexible tubes 20 that are also attached to the under surface of the canopy. When this tubular network is suddenly filled with gas, it will bulge out the canopy to assist in forcing it from the pack 6 and opening it to its maximum limits within a short period of time. This gas which the upper compartment 19 receives will make 90 it sufficiently buoyant to materially assist in carrying the parachute user slowly to the ground.

For the purpose of releasing gas from the tank 7 at the same time the rip cord 21 of the 100

pack 6 is pulled, we attach the wire 15 to the inner end of the cord.

Therefore, when the pack is opened by the rip cord, the valve on the tank will be operated at the same time to permit gas to rush into the tubular network within the canopy to force it out of the pack, open it up and hold it open for a slow and safe descent.

Having described our invention, we claim:

- 10 1. The combination with a parachute, of flexible tubing secured to the canopy thereof, a gas tank carried by said parachute in communication with said flexible tubing, a valve for admitting gas to the latter from the tank, a slideable closure member in said valve, a spring for moving said closure member to a position to permit the flow of gas from the tank to the tubing, a pack for containing said parachute and tank, a rip cord for opening said pack, and a wire for holding said valve closure member in a closed position against the tension of said spring, said wire being secured to the rip cord and adapted to be drawn by it from the valve to release the latter when the rip cord is pulled to open the pack.
- 15 2. The combination with a parachute, of a flexible receptacle secured to the canopy thereof, a gas tank carried by said parachute in communication with said flexible receptacle, a valve for admitting gas to the latter from the tank, a closure member in said valve, a pack for containing said parachute and tank, a rip cord for opening said pack, and means for holding said valve closure member in a closed position, said means being secured to the rip cord and adapted to be drawn by it to open the valve when the rip cord is pulled to open the pack.
- 20 30 35 40 45 40 In testimony whereof we have hereunto set our hands this 29th day of September, 1930.

THOMAS B. BROWN.
MARION L. STANSELL.
